[57] ABSTRACT

This invention relates to an improved kite having a body of sheet material secured to supports and having a steadyng and guiding keel attached to the body. The sheet material has one or more openings so that the keel may be attached partly to a support and partly to the sheet material, thereby making the keel less likely to tear away from the kite body.

KITE

This invention relates generally to keel kites, and particularly to a keel kite wherein improved means are provided for securing the steadyng and guiding keel to the kite body.

Keel kites as heretofore known in the art have comprised a body portion, rigidifying structural members and a guiding, steadyng keel basically triangular in shape, and having an eyelet or other means for attaching a flying string. An example of this type of kite is shown in the U.S. Pat. to Green No. 2,785,870, issued March 19, 1957. A continuing problem with this type of kite has been that the keel tends to tear away from the body portion when the kite is subjected to extra loading due to a gust of wind or a sudden tug on the flying string.

It is therefore a primary object of this invention to provide a keel kite which is more durable than those heretofore known.

Another object is to provide such a kite wherein means are provided for securing the keel partly to a rigidifying structural member so as to make the keel less likely to separate from the kite body.

These and other objects and advantages of the invention will become apparent from the drawing, the specification and the claims.

BRIEF DESCRIPTION OF THE DRAWINGS

In the accompanying drawings, which illustrate the preferred embodiment of the present invention, and wherein like numerals indicate like parts:

FIG. 1 is a perspective view of a kite constructed in accordance with the present invention;

FIG. 2 is a plan view, partly cut away, of the kite of FIG. 1;

FIG. 3 is an enlarged elevational view taken along line 3—3 of FIG. 2.

DESCRIPTION OF THE PREFERRED EMBODIMENTS

Referring now to FIG. 1, there is shown a keel kite comprising generally a body portion 10 and a keel 11. The kite body 10 is made up of a polygonal sheet 12 of thin, flexible material such as plastic film, and of structural means for supporting the sheet in its extended flying position. In our preferred form of kite, these structural means are provided as follows: A center support 13 of suitable material, such as wood or plastic, is secured to sheet 12 preferably by means of an adhesive 14 disposed between the sheet 12 and support 13. The center support 13 is at least approximately as long as sheet 12 and is secured so as to divide sheet 12 into two mirror sections. Two side supports 15 and 16 are secured to opposite edges of sheet 12, one being on either side of the center support 13. Two connectors 17 are mounted, one on each of the side supports 15 and 16, and are adapted to engage opposite ends of a cross-brace 18 which serves to maintain the kite in its extended flying position. The keel 11, which is also formed of thin, flexible material, such as that of sheet 12, is preferably in the approximate shape of a triangle having its longest side attached to the kite body 12, preferably by attaching the keel 11 to sheet 12, and at least partially by adhesively securing keel 11 to center support 13 at one or more points, as will be hereinafter described. In the preferred embodiment, the keel 11 is

attached to sheet 12 along the center line of sheet 12 approximately directly below the center support 13. In those forms of the kite where the keel 11 and the center support 13 extend beyond sheet 12, as shown in FIG. 1, then keel 11 is, of course, attached to center support 13 along that portion of its length extending beyond sheet 12. A reinforced eyelet 19 for attaching a flying string 20 is provided near the free apex of keel 11.

As pointed out above, a major problem with keel kites has been a tendency on the part of the keel to tear away from the kite body. Separation of the keel from the body most frequently initiates at or near the leading point of the keel's attachment to the body. Once this leading point yields, the remainder of the failure occurs rather quickly. The kite of the present invention overcomes this disadvantage by providing means whereby the keel is adhesively secured directly to the center support 13, at least at one point near the keel's leading point of attachment to the kite body 10, thereby reinforcing the attachment at that point and making the keel less likely to tear away.

In the preferred manner of manufacturing keel kites, the supports, having an adhesive on their upper sides, are disposed on a work area, the sheet 12 is placed across the supports, and the keel 11 is placed on the sheet 12. Heat is then applied to adhesively bond the sheet 12 to the supports and to heat-bond the keel to the sheet 12. Experience has shown the adhesive bond to be stronger than the heat bond. Therefore, adhesive bonding of the keel to the sheet 12 would help prevent separation of the keel, but would also add an extra step and increased cost to the manufacturing process. The kite of the present invention provides the advantage of adhesive bonding without adding steps or increasing costs by providing one or more openings 21 in sheet 12 whereby the portion of keel 11 overlying an opening 21 is exposed directly to adhesive 14 and is consequently adhesively secured to center support 13 at those points.

One such opening 21 at or near the leading point of the keel's attachment to the kite body sufficiently reinforces that point to significantly reduce failure due to keel separation. If desired, a plurality of openings 21 may be provided as shown in FIG. 2 throughout the entire length of attachment of the keel to sheet 12. Of course, the openings should not be so numerous or so close together as to reduce the strength of sheet 12 below an acceptable level.

The foregoing disclosure and description of the invention is illustrative and explanatory thereof, and various changes in the size, shape and materials, as well as in the details of the illustrated construction, may be made within the scope of the appended claims without departing from the spirit of the invention.

What is claimed is:

1. A kite comprising, a body having a sheet of flexible material secured to structural means for supporting said sheet in an extended flying position, and

a keel disposed on the opposite side of said sheet from said structural means and attached to said body,

said sheet having at least one opening therein so that said keel is directly secured to said structural means through said opening and is attached to the remainder of said sheet along a line opposite said structural means.

2. The kite according to claim 1 wherein said keel is adhesively secured to said structural means near the foremost point of said keel's attachment to said body.

3. The kite according to claim 1 wherein a plurality of openings are provided spaced along the length of said keel's attachment to said body.

4. A kite comprising,
a polygonal sheet of flexible material,
first and second structural members secured to said sheet near opposite edges thereof,
connector means associated with said first and second structural members,
a cross-brace adapted to engage said connector means while retaining said sheet in extended flying position,
a third structural member secured to said sheet by means of an adhesive,

said third structural member being disposed intermediate said first and second structural members and dividing said sheet into two mirror image sections,

a keel of flexible material disposed on the side of said sheet opposite said structural members and approximately aligned with said third structural member,

said sheet having at least one opening in registry with said third structural member,
said keel being directly secured through said opening to said third structural member by said adhesive and being attached to said sheet at the sides of said opening along a line on the side of said sheet opposite said third structural member.
